CLAIM

The ornamental design for a pet cage, as shown and described.

DESCRIPTION

FIG. 1 is a perspective view of a pet cage, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion of FIG. 1 thereof;

FIG. 10 is an enlarged view of portion of FIG. 1 thereof;

FIG. 11 is an enlarged view of portion of FIG. 1 thereof;

FIG. 12 is an enlarged view of portion of FIG. 2 thereof; and,

FIG. 13 is an enlarged view of portion of FIG. 2.

The dot-dash lines enclosing the enlarged portions are for depicting the boundary lines of the enlarged views and form no part of the claimed design.
